UNITED STATES PATENT OFFICE.

EDGAR L. FULLER, OF EVERETT, MASSACHUSETTS.

MATTERESS-COVER.

948,684.

Specification of Letters Patent.

Patented Feb. 8, 1910.

Application filed October 26, 1908. Serial No. 459,463.

To all whom it may concern:

Be it known that I, EDGAR L. FULLER, a citizen of the United States, residing in Everett, in the county of Middlesex and 5 State of Massachusetts, have invented an Improvement in Mattress-Covers, of which the following description, in connection with the accompanying drawings, is a specification, like letters on the drawings representing 10 like parts.

This invention relates to a mattress cover, which is especially designed and adapted among other uses to be employed with a bed having a wire mattress or bottom, and more 15 particularly with a folding bed, such as shown and described in U. S. Patent No. 777,284 granted to me December 13, 1904.

Beds of the class described are designed to be used in restricted quarters, and the 20 present invention has for its object to provide means which will enable a tufted or other mattress of any suitable or usual construction to be used on such beds and be secured thereto in a practically permanent 25 manner, while at the same time affording a protective removable covering for the mattress.

Beds of the class described are used extensively in immigrant stations and like 30 places and the cover for the mattress serves to protect the same against dirt and from being soiled by the occupants of the bed, while at the same time it serves to secure the mattress to the bed so as to permit the 35 latter to be folded up with the mattress thereon.

The cover is detachable from the mattress, and can be quickly and easily washed and kept in a clean and wholesome condition. 40 To this end, the cover, which may be made of any suitable fabric, is provided with pockets at its ends for the reception of the ends of the mattress and with a movable section or flap intermediate of said pockets, 45 which is designed to be extended under the wire bottom of the bed and then be attached to the portion of the cover intermediate its pockets to firmly secure the mattress to the wire bottom of the bed and to complete the 50 covering for the tufted mattress. These and other features of this invention will be pointed out in the claims at the end of this specification.

Figure 1 is an elevation of a folding bed 55 provided with a mattress secured thereto by a cover embodying this invention. Fig. 2, a

cross section on the line 2—2, Fig. 1. Fig. 3 a perspective of the cover removed, and Fig. 4, a developed view of a blank from which the cover may be made.

60

Referring to the drawings, *a* represents a bed frame, which is provided with a bottom *b* usually of wire, and is pivotally connected to upright posts *c* so as to be capable of being folded up substantially parallel 65 with said posts when the bed is not in use, and which is supported by brackets *d* and braces *e* in its horizontal position when the bed is in use, said parts being substantially such as shown and described in the patent 70 above referred to.

The bed bottom *b* supports a mattress *f*, which may be of any usual or suitable construction and which may be referred to as the tufted mattress to distinguish it from 75 the bed bottom *b*, which is usually referred to as the wire mattress in beds of this class.

The tufted mattress *f* in accordance with this invention is secured to the bottom *b* of the bed, by a cover preferably made as herein shown (see Fig. 3) and provided with end pockets 10, 12, into which the ends of the tufted mattress *f* may be inserted, a top 13 to engage the top of the mattress *f*, and a movable section or flap 14, which is intermediate the end pockets and is designed to be passed under the wire mattress or bottom 80 *b* and detachably secured to the top 13 by fastening devices 15, 16, which may be like the ball and socket members of a glove fastening or which may be of any other suitable or desired construction.

The cover shown in Fig. 3, may be made from a single piece of fabric or blank shown in Fig. 4, by providing the blank with slits 95 or cuts 20, 21, which extend from one side of the blank substantially one-half the width of the latter and form loose sections or ends 22, 23, which may be folded over upon the uncut ends and stitched or otherwise secured together to form the end pockets 10, 12, after which the cover may be turned inside out if desired to avoid showing the stitched edges and to obtain a finished appearance on the outside of the cover.

I may prefer to make the cover from a single piece or blank as herein represented but I do not desire to limit my invention in this respect, and while I may prefer to use the form of fastening devices herein described and represented for securing the flap 14 to the body portion or top 13 of the 100 105 110

cover, I do not desire to limit my invention in this respect. So also I may prefer to close the ends of the pockets, but I do not desire to limit my invention in this respect.

5. By making the flap or intermediate section 14 separate from the end pockets a break is obtained at each end of the cover, which enables either end of the mattress to be raised by the insertion of suitable material 25 beneath the same so as to convert said end into a pillow for the head of the occupant of the bed, after the manner represented in Fig. 1.

15. From the above description and by reference to the drawings, it will be seen that the tufted mattress *f* is firmly secured to the bed bottom *b* so as to move therewith when the bed frame is moved into its operative or inoperative position, while at the same time 20 the tufted mattress is protected by the cover from being soiled by the occupant of the bed and from the dust of the place in which the bed is located, and further that the cover can be readily and quickly removed for 25 washing or otherwise cleaning the same. So also the flap 14 passing under the bed bottom *b* serves to protect the same from moisture.

Claims.

30. 1. The combination with a bed provided with a bottom, of a mattress supported by said bottom, a cover for said mattress having end pockets for the reception of the mattress and an intermediate portion which 35 is extended under the bottom of the bed, and means for securing the said intermediate portion to the portion of the cover above the said bottom, substantially as described.
2. The combination with a bed provided 40 with a bottom, of a mattress supported by

said bottom, a cover for said mattress having end pockets for the reception of the ends of the mattress, means extended under the bottom of said bed and attached to the cover on opposite sides of the said bed bottom to 45 secure the mattress to said bed bottom, substantially as described.

3. A mattress cover provided with end pockets for the reception of the ends of the mattress, and with a movable section or flap 50 intermediate the said pockets and capable of being turned back to render both end pockets accessible for the insertion of the mattress, for the purpose specified.

4. A mattress cover comprising a single 55 piece of fabric having a top to engage one surface of the mattress, end pockets for the reception of the ends of the mattress, and a flap or movable section intermediate the end pockets and capable of rendering them 60 simultaneously accessible, substantially as described.

5. A mattress cover provided with end pockets for the reception of the ends of the mattress and with top and bottom parts 65 intermediate said end pockets, one of said parts being detachably secured to the other to render the end pockets simultaneously accessible for the insertion of the mattress and to enable the detachable part to be passed 70 under the bed bottom upon which the covered mattress is supported, for the purpose specified.

In testimony whereof, I have signed my name to this specification in the presence of 75 two subscribing witnesses.

EDGAR L. FULLER.
